UNITED STATES PATENT OFFICE

2,088,870

VACUUM MASSAGING DEVICE

Charles Reid, Winnipeg, Manitoba, Canada, assignor of one-half to Louis Rezek, Winnipeg, Manitoba, Canada

Application July 24, 1936, Serial No. 92,439

1 Claim. (Cl. 128—297)

This invention relates to improvements in vacuum massaging devices and an object of the invention is to provide a device of the character herein described which when passed over the skin will, by vacuum action, draw blood to the superficial layer thereof and remove secretions exuded from the pores, thus toning and cleansing the skin.

A further object of the invention is to provide a device of the character herein described which, when passed over the scalp, will, by suction, remove dandruff and invigorate the tissues of the scalp, thereby stimulating a healthy growth of hair.

15 A further object of my invention is to provide a device of the character herein described which is provided with filtering means to remove all foreign matter from the air passing through the device before it reaches the outer atmosphere.

20 A further object of the invention is to provide a device of the character herein described, which may be conveniently disassembled for cleaning purposes or for changing the filter.

25 A further object of the invention is to provide a device of the character herein described which may be used as a blower or as a means for supplying a blast of air when used with such attachments as atomizers, etc.

30 A still further object of the invention is to provide a device of the character herein described which is simple to construct, economical to manufacture, and will not easily become out of order.

35 With the above more important objects in view and such other minor objects as may appear as the specification proceeds, my invention consists essentially in the arrangement and construction of parts all as hereinafter more particularly described, reference being had to the accompanying drawing, in which:—

40 Fig. 1 illustrates a side elevation of my improved type of massaging device with a portion of the casing thereof shown in section.

Fig. 2 is a central sectional elevation of the forward portion of the device.

45 Fig. 3 is an inverted view of the mouthpiece used with the machine.

In the drawing like characters of reference indicate corresponding parts in the different figures.

50 This invention consists of a cylindrical casing 1, to the lower surface of which is attached a handle 2. The forward end 3 of the cylinder is reduced in diameter and is provided with a conduit 4 extending centrally therethrough. Over this conduit is received the rear portion 5 of the

filter housing which is maintained in position by a set screw 6.

An internally threaded flange 7 extends forwardly from the periphery of the portion 5 and the junction between the flange and the housing 5 provides a shoulder 8.

Threadably received by the flange 7 is a cap 9 having a hollow boss 10 extending centrally therethrough. This cap is also provided with an annular shoulder 11 in opposition to the shoulder 10 and between these shoulders is placed a wire screen 12 designed to receive a layer of filtering material 13 thereover. This material may be paper or cloth and can be medicated if so desired. A wire ring 14 is inserted between the filter and the shoulder 11 to prevent damage to the filter when the cap is screwed into the position illustrated.

Receivable over the outer periphery of the boss 10 is an elbow 15 which is provided with an enlarged flange 16 at the lower end thereof. Within this flange is an annular recess 17 which is designed to receive a mouthpiece 18. This mouthpiece is maintained in position by means of a pin 19 receivable by a bayonet joint 20 within the flange 16. The mouthpiece is flared outwardly as shown and is preferably made of wood or other non-metallic substance, and the lower edge thereof is provided with an annular semicircular groove 21 which encircles the aperture 22 and is provided for a purpose presently to be explained.

Within the casing 1 is an electric motor 23 which is spaced from the casing and is held firmly in position by bolts 24. A propeller 25 is affixed to the forward end of the motor shaft and is designed to cause a blast of air to move inwardly through the mouthpiece 22. An electric cable 26 passes through the casing and is adapted to carry the current for the motor 23. A toggle switch 27 is conveniently located adjacent the handle 2 in order to control the operation of the motor.

The rear end 28 of the casing is also reduced in diameter in a manner similar to the forward end thereof, and is provided with a nozzle 29 from which the air, after passing through the device, may be expelled. This nozzle, it should be noted, has a uniform diameter for a portion of the length thereof, and is adapted to receive an atomizer or other device which requires a current of air for operation.

Having described the structure of the device, the mode of operation thereof will now be presented.

When the unit is to be used for massaging the skin, any one of the usual massaging preparations is applied to the skin surface, the motor 23 is actuated and the mouthpiece 18 is then passed thereover. The suction produced by the device will draw blood to the superficial layer of the skin which will, in turn, cause the pores to open so that any secretions may be withdrawn therefrom and the device will thus invigorate and cleanse the skin simultaneously.

When the device is used for massaging the scalp, it has been found to have a highly beneficial effect thereon in that the blood is caused to flow in the surface layers of the skin due to the vacuum action. The device is also very effective in removing dandruff and other foreign matter from the hair.

When the machine is used with a mouthpiece which does not have the annular groove 21, it has been found to remove only a fraction of the dandruff from the hair. However, with the annular groove, practically complete removal of the dandruff can be effected. The action of this groove is not clearly understood, but it is believed that the vibration of the machine combined with the suction causes the hairs to bend or kink and thereby throw off the dandruff which is caught in the air stream and carried into the machine.

After each application of the machine, the filter 13 may be removed and another substituted therefor.

It should be mentioned that if the device is to be used as a blower, heated air can also be expelled therefrom by placing an electrical element across the space behind the motor 23.

From the foregoing, it will now be evident that I have provided a highly efficient type of massaging device by means of which a massage can be effected more efficiently and with greater despatch than has hitherto been the case.

Since various modifications can be made in the above invention, and many apparently widely different embodiments of same, made within the scope of the claims without departing from the spirit and scope thereof, it is intended that all matter contained in the accompanying specification shall be interpreted as illustrative only and not in a limiting sense and I desire only such limitations placed thereon as are specifically expressed in the accompanying claim.

What I claim as my invention is:—

A vacuum massaging device comprising a casing, a fan situated within said casing and spaced from the wall thereof, a conduit extending from the interior of said casing and communicating with a filtering chamber, a removable filter within said chamber and a tube extending from said chamber on the opposite side of said filter to the point of entrance of said conduit, a mouthpiece attachable to said tube, said mouthpiece being designed to engage with the hair or skin of a person undergoing treatment.

CHARLES REID.
